PHASING SIMULATOR FOR A MUSICAL INSTRUMENT

Keith Barr, 25 Southland Drive,
Rochester, N.Y. 14623

Filed Feb. 6, 1974, Ser. No. 440,149

Term of patent 14 years

Int. Cl. D13—03

U.S. Cl. D26—13 C

FIG. 1

FIG. 2

FIG. 3

FIG. 4

FIG. 5

FIG. 6

FIG. 1 is a top plan view of a phasing simulator for a musical instrument showing my new design;

FIG. 2 is a right side elevational view;

FIG. 3 is a bottom plan view;

FIG. 4 is a front end elevational view;

FIG. 5 is a rear end elevational view; and

FIG. 6 is a top plan view of another embodiment of a phasing simulator for a musical instrument showing my new design.

I claim:

The ornamental design for a phasing simulator for a musical instrument, substantially as shown.
